UNITED STATES PATENT OFFICE.

CHARLES SEYMOUR, OF DEFIANCE, OHIO, ASSIGNOR TO THE DEFIANCE MACHINE WORKS, OF DEFIANCE, OHIO.

FRICTION-CLUTCH.

SPECIFICATION forming part of Letters Patent No. 766,534, dated August 2, 1904.

Original application filed January 30, 1904, Serial No. 191,272. Divided and this application filed April 29, 1904. Serial No. 205,458. (No model.)

To all whom it may concern:

Be it known that I, CHARLES SEYMOUR, a citizen of the United States, and a resident of Defiance, in the county of Defiance and State of Ohio, have invented a new and Improved Friction-Clutch, of which the following is a full, clear, and exact description, this being a division of the application for Letters Patent of the United States for a band-saw, Serial No. 191,272, filed by me January 30, 1904.

The object of the invention is to provide a new and improved friction-clutch arranged to hold a movable part under ordinary conditions in position, to allow a limited yielding movement of the said part when under an ordinary strain, and to permit the part to move any desired distance when under an excessive strain.

The invention consists of novel features and parts and combinations of the same, as will be more fully described hereinafter and then pointed out in the claim.

A practical embodiment of the invention is represented in the accompanying drawings, forming a part of this specification, in which similar characters of reference indicate corresponding parts in both views.

Figure 1 is cross-section of the improvement as applied to a rack-and-pinion movement for raising or lowering the sliding head of a band-saw, and Fig. 2 is a sectional front elevation of the same on the line 2 2 of Fig. 1.

The improved friction-clutch forming the subject-matter of this application is more especially designed for use on the raising and lowering mechanism for the head of a band-saw, which head carries the feed mechanism for feeding the work transversely over the saw-table; but it is evident that the friction-clutch may be used on other mechanisms and devices, if desired.

A rack K', in mesh with a pinion K², is employed for imparting movement to the head or other part to be raised or lowered, and the said pinion K² is fastened or formed on a shaft K³, journaled in a suitable bearing E⁸, carried on the main frame E of the machine on which the device is used. On the outer end of the

shaft K³ is secured a hand-wheel K⁴, adapted to be turned by the operator to rotate the shaft K³ for the pinion K² to impart a sliding motion to the rack K' and the head in either direction, according to the direction in which the hand-wheel K⁴ is turned. By moving the head the feed mechanism thereon is moved in proper contact with the top face of the work to be fed across the saw-table.

In order to lock the shaft K³, and consequently the head, in position, but to allow a limited yielding movement of the head to compensate for any inequalities in the work, the following friction-clutch is provided: On the shaft K³ is secured a friction-disk O, having a peripheral groove O', approximately U-shaped in cross-section and in which fits a correspondingly-shaped friction-block O², engaged by a handled screw-rod O³, screwing in a yoke O⁴, mounted to turn loosely on the friction-disk O. The yoke O⁴ is provided with an arm O⁵, adapted to abut against either of the stops O⁶ or O⁷, attached to the flange E⁹ of the bearing E⁸, the said stop serving to limit the oscillating movement of the yoke O⁴. By screwing the screw-rod O³ downward the block O² is forced with more or less force in frictional contact with the friction-disk O, so as to normally hold the latter against turning, but in case of an undue strain in an upward direction against the head and rack K' the pinion K² and its shaft K³ can turn, so as to swing the arm O⁵ from the stop O⁶ over toward the stop O⁷, thereby allowing the head to yield sufficiently to compensate for an increase in thickness of the work passing over the saw-table and under the feed mechanism of the head. The weight of the head and the parts supported thereby is sufficient to return the head in a downward direction in case the work decreases in height, so that the arm O⁵ again moves over to the stop O⁶, and in case of an excessive strain the block O² will slide in the groove O' of the friction-disk O, so that the head may be moved any desired distance upward, provided sufficient force is employed to move the head in an upward direction.

From the foregoing it will be seen that the

friction-clutch holds the shaft K^3 under ordinary conditions against turning, but in case of a strain the shaft K^3 has a limited turning motion, and in case of an excessive strain the 5 shaft K^3 may make one or more revolutions.

When it is desired to freely actuate the rack-and-pinion movement for raising or lowering the head, then it is only necessary for the operator to unscrew the screw-rod O^3 to relieve 10 the friction-disk O of the friction by the friction-block O^2 , so that the operator on turning the hand-wheel K^4 can readily turn the shaft K^3 for the desired purpose.

Having thus described my invention, I claim 15 as new and desire to secure by Letters Patent—

A friction-clutch for a shaft or similar rotating part, comprising a friction-disk secured

on the said part, a friction-block in peripheral engagement with the said friction-disk, a yoke peripherally fitting the said friction-disk, 20 a screw-rod screwing in the said yoke and engaging the said friction-block, for holding the latter with more or less force in frictional contact with the said friction-disk, and fixed means for limiting the oscillating motion of the 25 said yoke.

In testimony whereof I have signed my name to this specification in the presence of two subscribing witnesses.

CHARLES SEYMOUR.
